US0D1099733S

(12) **United States Design Patent** (10) **Patent No.:** **US D1,099,733 S**
(45) **Date of Patent:** **** Oct. 28, 2025**

(54) **SOLAR-CHARGING MOUNTING BRACKET**

(71) Applicant: **Amazon Technologies, Inc.**, Seattle, WA (US)

(72) Inventors: **James Siminoff**, Pacific Palisades, CA (US); **Spiro Sacre**, Los Angeles, CA (US); **Christopher Loew**, Palo Alto, CA (US); **Mark D Siminoff**, Mountain View, CA (US)

(73) Assignee: **Amazon Technologies, Inc.**, Seattle, WA (US)

(**) Term: **15 Years**

(21) Appl. No.: **29/876,269**

(22) Filed: **May 18, 2023**

Related U.S. Application Data

(63) Continuation of application No. 29/699,188, filed on Jul. 23, 2019, now Pat. No. Des. 988,897, which is a continuation of application No. 29/595,956, filed on Mar. 3, 2017, now Pat. No. Des. 856,839.

(57) **CLAIM**

The ornamental design for a solar-charging mounting bracket, as shown and described.

DESCRIPTION

FIG. 1 is a front, top, right-side perspective view of a solar-charging mounting bracket;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dashed broken lines depict portions of the solar-charging mounting bracket that form no part of the claimed design.

1 Claim, 5 Drawing Sheets
